UNITED STATES PATENT OFFICE

McCLURE W. COWAN AND DAVID FELTEN, OF PARSONS, KANSAS.

OIL-BURNER.

949,648.

Specification of Letters Patent. Patented Feb. 15, 1910.

Application filed May 25, 1909. Serial No. 498,129.

To all whom it may concern:

Be it known that we, McCLURE W. COWAN and DAVID FELTEN, citizens of the United States, residing at Parsons, in the county of Labette and State of Kansas, have invented new and useful Improvements in Oil-Burners, of which the following is a specification.

This invention relates to improvements in crude oil burners adapted for use in heating stoves and also for use in the furnaces of steam boilers and for other analogous purposes, the object of the invention being to provide a novel form of burner which is not liable to become clogged with the oil when in use and which vaporizes the oil and burns the vapor, thereby effecting a complete combustion of the oil and producing no smoke.

With these and other objects in view, the invention consists in the construction, combination and arrangement of devices hereinafter described and claimed.

The accompanying drawing is a sectional view of a crude oil burner constructed in accordance with our invention, showing the same for use in a heating stove, the latter forming a casing.

In accordance with our invention, we provide a downwardly extending air inlet and heating chamber which in the embodiment of the invention here shown is open at its lower end, is provided at its upper end with a laterally inclined intake arm or portion 2 and is cylindrical in form. The said chamber may have its walls constructed of any suitable material such as iron or steel and in practice, is disposed in an outer casing which is here indicated as the casing 3 of a heating stove. The intake arm 2 of the said chamber 1 extends and is attached to one side of the outer casing 3 as at 4 and communicates with an air intake opening 5, which may be opened or closed to any desired extent by a valve or draft device 6. The stove is shown as provided near its upper end with an inclined baffle 7 and with a smoke pipe 8. In the lower portion of the stove is a pan 9, corresponding with an ash pan, and above the same is a basin shaped netting 10 in which ignited material may be placed for the purpose of generating heat to start the burner in operation. The said netting is here shown as supported on one side by a bracket 11 and on the opposite side by an arm 12. Any suitable supporting means may be employed. The said netting is disposed under and at a suitable distance below

the chamber 1. The stove is provided with the usual door 13 to enable the pan 9 to be placed in or removed therefrom and with the usual door 14 corresponding with a fire door, the same being located at such point as to render the netting 10 and the lower portion of the chamber 1 readily accessible.

In chamber 1 is a vaporizer 15 which is here shown as bell shaped or conical, is open at its lower end and is provided near its lower end with a series of openings 16 to admit air to the interior of the vaporizer from the chamber 1. The retort is here shown as formed at its upper end with a cylindrical portion 17 to which is connected the lower end of an oil feed pipe 18 having a bore of suitable diameter, the said pipe being disposed in an upright position and in practice leading downwardly from a suitable reservoir or vessel containing crude oil. In practice, a suitable valve will be employed to regulate the flow of crude oil downwardly through the feed pipe 18 to the bell or vaporizer. It will be observed that the lower end of the oil feed pipe terminates in the upper end of the bell-shaped vaporizer. In practice the flow of oil through the pipe is so controlled by the valve that the oil is caused to pass slowly through the pipe and in a small quantity so that the oil spreads on the inner surface of the pipe and also spreads on the inner surface of the bell or vaporizer, hence, the interior surface of the wall of the bell-shaped vaporizer is supplied with oil continuously by the said pipe. Assuming that the bell or vaporizer has been initially heated to the requisite degree, the crude oil as it comes downwardly through the pipe 18 will be converted into gas in the retort both by direct contact with the heated interior surface of the vaporizer and by the heat reflected therefrom. The air in descending through the chamber 1 will be heated both by the walls of said chamber and by the exterior of the heated vaporizer and hence the air which enters the vaporizer at the lower open end thereof through the openings 16 from the chamber 1 will be heated and will commingle with the heated gases or vapors from the vaporizer and hence such commingled air and gases or vapors will burn below the vaporizer and in the casing 3, as will be understood. The products of combustion pass off through the draft pipe 8. The pan 9 serves to receive soot and other unconsumed particles which

drop from the burner and interior surface of the casing and permits the ready removal of such particles.

Owing to the fact that the retort is at 5 the lower end of the feed pipe and that the oil passes downwardly through said feed pipe to the vaporizer, the oil is effectually prevented from clogging up the feed pipe and its flow to the vaporizer is uninterrupted 10 while the controlling valve of the said pipe is open. Water, if any in the oil, will not effect the operation of the burner but will be vaporized and its vapor will commingle with the vapors or gases from 15 the oil and with the heated air in the vaporizer and combustion will uninterruptedly proceed.

It will be obvious that our burner may be used in any other casing as well as in connection with a stove as here shown and will 20 be found particularly useful in the furnaces of steam boilers.

What is claimed is:—

A crude oil burner comprising a casing,

an air inlet chamber therein having its walls 25 spaced from those of the casing and provided at its upper end with an inlet for atmospheric air, an oil pipe extending downwardly through said chamber, and a bell-shaped vaporizer disposed in the lower end 30 of said chamber, said vaporizer and said chamber having coincident lower ends, the lower end of said vaporizer being open and said vaporizer being provided with openings 35 in its walls near its lower open end to admit air from said chamber to the interior of said vaporizer, the said pipe terminating at and discharging into the upper end of the said vaporizer to supply the interior surface of the vaporizer with oil. 40

In testimony whereof we affix our signatures in presence of two witnesses.

McCORMICK W. COWAN.
